UNITED STATES PATENT OFFICE.

ROBERT ALBRECHT, OF RACINE, WISCONSIN, ASSIGNOR TO HAMILTON BEACH MFG. CO., OF RACINE, WISCONSIN, A CORPORATION OF WISCONSIN.

MOTOR MOUNTING.

Application filed May 5, 1926. Serial No. 106,924.

This invention relates to improvements in motor mountings, particularly adapted for yieldingly securing flat type electric motors to the head portions of sewing machines for 5 electrically propelling the machine hand wheel.

It is one of the objects of the present invention to provide a motor mounting for sewing machines adapted to yieldingly hold 10 a motor in a hand wheel engaging position and so arranged that the mounting and motor may be manually pivoted to a position of disengagement with respect to the hand wheel but which automatically returns to 15 normal position immediately upon being released.

A further object of the invention is to provide a yieldingly pivotal motor mounting adapted for rigid attachment to the side 20 portion of a sewing machine head.

A further object of the invention is to provide a motor mounting for sewing machine heads having an adjustable wedge by 25 which means the mounting and motor may be locked in a tilted position with the motor pulley wheel out of contact with the hand wheel to permit bobbin winding.

A further object of the invention is to provide a motor mounting of the class described which is of very simple construction, is easily installed on a sewing machine head, is strong and durable, and is well adapted for the purposes described.

With the above and other objects in view, 30 the invention consists of the improved motor mounting, and its parts and combinations as set forth in the claims, and all equivalents thereof.

In the accompanying drawing, in which 35 the same reference characters indicate the same parts in all of the views:

Fig. 1 is an end view of a sewing machine head having the improved motor mounting attached thereto and holding the pulley 40 wheel of a motor in engagement with the machine hand wheel;

Fig. 2 is a side view of the same;

Fig. 3 is a sectional view taken on line 3-3 of Fig. 2;

Fig. 4 is a fragmentary plan view illustrating a modified form of the invention; and

Fig. 5 is a side view thereof.

Referring now more particularly to Figs. 51, 2 and 3, of the drawings and the form

of the invention disclosed thereby, it will be seen that the numeral 8 designates a sewing machine head, revolubly carrying a hand wheel 9.

Secured to the side of the head 8 is one 60 arm of an angular bracket member 10 bent at an angle slightly greater than a right angle. The extending arm portion of the bracket member is provided at its outer side edge portions with a pair of depending 65 apertured ears 11. Positioned above the said portion of the bracket member is a saddle member 12 also having depending apertured ears 13 which are adjacent the ears 11, as shown in Fig. 2. A pivot rod 14 70 is extended through the registering apertures of all of said ears, whereby the saddle member may pivot on the rod with respect to the bracket member and head.

A small flat type electric motor 15 is fastened to and carried by the saddle member in such a position that the pulley wheel 16 thereof is normally in frictional engagement with the hand wheel 9 to drive the 75 same.

For the purpose of locking the mounting in disengaging position, a slidable bar or wedge member 17 is provided. Said bar member is interposed between the saddle member and the angular member 10, and it 80 is provided with a medial longitudinal slot 18 through which the shank of a screw 19 extends, the end portion of the screw being threaded into the saddle member. Said screw also extends through the angular 90 member 10, and a spring 20 coiled about said screw is confined between the screw head and a washer adjacent the undersurface of the member 10. One end of the bar member 17 is formed with an operating ear 95 21 for manipulation, while the other end portion is off-set and inclined downwardly, as at 22.

In the normal position of the device shown in the drawings, the mounting is so 100 positioned that the pulley wheel is in frictional engagement with the hand wheel. By tightening or loosening the screw 19, the tension exerted by the pulley against the hand wheel may be increased or decreased. 105 Due to the fact that the pivot point of the mounting is in alinement with the vertical center line of the motor, a slight outward pivotal movement will be sufficient to disengage the pulley and hand wheels, as 110

shown by dotted lines in Fig. 1. This is accomplished by sliding the bar member 17 to the left in Fig. 2 whereby the off-set portion 22 is interposed between the saddle and bracket members to tilt the saddle forwardly. With the pulley wheel thus disengaged, bobbins may be readily wound. When the bar is returned to normal position, the expansion of the spring 20 will return the mounting to normal position.

The form of the invention shown in Figs. 4 and 5 discloses a bracket or mounting of a hinge type. One hinge member 23 is secured to the side of the head 8 and said member has the usual tubular off-set bolt receiving portions 24. A complementary hinge member 25 is secured to the motor 15 with its off-set tubular portions 26 in vertical alinement with the portions 24. A rod or bolt 27 extends through said tubular portions to pivotally join the complementary hinge members.

Coiled about the bolt 27 between the portions 26 is a spring 28 having its end portions extending horizontally. One end portion bears against the head, as at 29, while the other end portion bears against the motor, as at 30.

With this arrangement, the motor may be hinged outwardly laterally away from the hand wheel. This movement will tend to wind the spring on the bolt and when the motor is released, the unwinding movement of the spring will automatically return the motor to its normal engaging position.

From the foregoing description it will be seen that the improved motor mounting is of very simple and novel construction, and is well adapted for the purposes set forth.

What I claim as my invention is:

1. The combination with a sewing machine head having a hand wheel, of a motor mounting, comprising a head engaging member secured to the head, a motor, a motor engaging member secured to said motor and hinged to the head engaging member, and a coiled spring having an expansive and contractile engagement between said members and exerting a force against said motor engaging member inwardly of its hinge connection to normally hold the pulley wheel of the motor in yielding engagement with said hand wheel.

2. The combination with a sewing machine head having a hand wheel, and a motor for driving said hand wheel, of a motor mounting comprising an angular bracket member secured to the side of said head, a saddle member secured to said motor and pivoted to said bracket member, and a manually, longitudinally movable member interposed between and engaging the bracket and saddle members for releasably locking the latter in a pivotal position whereby the motor is held away from the hand wheel.

3. The combination with a sewing machine head having a hand wheel, and a motor for driving said hand wheel, of a motor mounting comprising an angular bracket member secured to said head, a saddle member secured to said motor and pivoted to said bracket member, and a wedge member engaging the bracket and saddle members for locking the latter in a pivoted position outwardly from the head.

4. The combination with a sewing machine head having a hand wheel, and a motor for driving said hand wheel, of a motor mounting comprising an angular bracket member secured to said head, a saddle member secured to said motor and pivoted to said bracket member, and a sliding wedge member interposed between the bracket and saddle members for releasably locking the latter in a pivoted position outwardly from the head.

5. The combination with a sewing machine head having a hand wheel, and a motor for driving said hand wheel, of a motor mounting comprising an angular bracket member secured to said head, a saddle member secured to said motor and pivoted to said bracket member, means engaging the bracket and saddle members for locking the latter in a pivoted position outwardly from the head, and a coiled spring confined so as to be contracted by an outward pivotal movement of said saddle member.

6. The combination with a sewing machine head having a hand wheel, and a motor for driving said hand wheel, of a motor mounting comprising an angular bracket member secured to the side of said head, a saddle member secured to said motor and pivoted to said bracket member, longitudinally adjustable means interposed between the bracket and saddle members for locking the latter in a pivoted position outwardly from the head, a coiled spring exerting a force against said saddle member, and means for adjusting said spring so as to exert more or less tension.

7. The combination with a sewing machine head having a hand wheel, and a motor for driving said hand wheel, of a motor mounting, comprising an angular bracket member secured to said head, a saddle member secured to said motor and medially pivotally attached to said bracket member, a slotted wedging member interposed between the inner portion of said saddle member and the bracket member, a screw extending through the slot of said wedging member and threaded into said saddle member, and a spring coiled about said screw and confined between the head thereof and the bracket member.

In testimony whereof, I affix my signature.

ROBERT ALBRECHT.
